AWNING TYPE WINDOW STRUCTURE AND OPERATING MEANS THEREFOR

Harry O. Roberts, Buffalo, N. Y., assignor to Air-Vue Products Corporation, Miami, Fla., a corporation of Florida

Application December 21, 1953, Serial No. 399,205

4 Claims. (Cl. 189—67)

This invention relates to windows of the louver or awning type, and more particularly to improved means for mounting the swinging sashes and opening and closing them. Windows of this character have a tier of sashes in the open area of a rectangular frame, and they are adapted to swing upwardly and outwardly from closed positions in a single vertical plane when an operating member on the inside of the frame is actuated.

The invention contemplates a window of this type in which the hinges at the upper corners of the sashes have a vertical sliding movement as the sashes swing in their opening and closing movements, and one object of the invention is to provide an improved mounting and actuating means for such sashes which will enable the sashes to be more effectively moved and held in their fully closed positions without applying undue force from the operator to the linkage.

Another object is to provide a sash mounting and actuating means of the above indicated character which is strong and sturdy in construction, capable of being manufactured at a relatively low cost, and highly effective in use.

Another object is to provide in a mechanism of this kind a very simple means to permit the sashes to be readily adjusted relative to each other and to the frame, so that the sashes will close tightly against the frame and contiguous sashes against each other.

With the above and other objects and advantages in view, the invention resides in the novel combinations and arrangements of parts and the novel features of construction hereinafter described and claimed, and illustrated in the accompanying drawings which show the present preferred embodiment of the invention.

In the drawings:

Fig. 1 is a vertical sectional view through a window showing the sashes in partially opened positions, parts being broken away;

Fig. 2 is a similar view on a slightly enlarged scale showing the sashes in closed position, parts being broken away and omitted, and the two sashes being shown partly in section and partly in edge elevation;

Fig. 3 is an enlarged horizontal section through the frame and one of the sashes in its closed position with parts being broken away, the plane of the section being indicated by the line 3—3 in Fig. 1;

Fig. 4 is a detail view of the left hand side of the front or outside of the frame with parts broken away and with the sashes omitted to show the arrangement of the sash operating linkage;

Fig. 5 is a detail vertical section through a portion of one jamb and a slideable hinge member for a sash, the plane of the section being indicated by the line 5—5 in Fig. 3;

Figs. 6 and 7 are respectively a side view and an edge view of one of the sash hinge members which are fastened to the upper corners of the sash;

Figs. 8 and 9 are detail sections taken respectively on

2

line 8—8 and 9—9 in Fig. 1 to show the adjustable pivot member or bracket for a sash supporting or fulcrum link;

Fig. 10 is a perspective view of the plastic slide shown in Fig. 5;

Fig. 11 is an enlarged vertical front-to-rear sectional view through the lower portion of the sill and of the jamb in which the screw and traveling nut operating mechanism is mounted; and

Fig. 12 is a detail front elevation on a reduced scale of the lower portion of the outer side of the frame.

Referring more in detail to the drawings, the numeral 15 denotes a rectangular window frame which may be suitably mounted in a wall 16 of any desired construction and within the open portion of which is a tier of sashes 17 mounted for both sliding and swinging movement. While only two sashes are shown, a greater number may be used. The frame 15 has a little 18, a sill 19 and jambs 20 and 21. All of these parts are preferably of hollow formation and made of suitably united sections of metal such as aluminum, some of which are extruded with grooves or undercut channels. The rectangular sashes 17 are also preferably made of suitably united aluminum sections of the Z-bar type, and each has a glass pane 22 fastened by putty 23 or other means.

Each sash is hung near its upper corners for outward swinging on a pair of longitudinally aligned pivots 25 and these pivots are mounted for sliding movement in vertical guides 26 in the jambs 20 and 21. The two or more sashes are connected for simultaneous swinging on the pivots 25 and vertical sliding, by vertical travel links 27 and fulcrum links 28. The links or bars 27 are disposed in the hollow jambs and simultaneously actuated by a mechanism in the sill and lower portions of the jambs as hereinafter described. At the side edges or ends of each sash the aligned fulcrum links 28 are pivoted at one end to the sash and at the other end to the jambs, the arrangement being such that the links 28 will cause the sashes to swing on the pivots 25 as the latter are caused to slide vertically in the guides 26 by the movement of the links 27. These guides, as shown in Fig. 3, are undercut channels formed by opposed L-shaped flanges 29 on the inner faces of the outer walls of the hollow jambs. The flanges extend continuously from a point near the top of the jamb to a point spaced above the sill, as seen in Fig. 3. They are formed when the jamb sections are extruded, and the portions of the flanges 29 not needed are cutaway. The pivots 25 are of metal and project through the open portions of the guide channels 26 from enlarged base portions or blocks shaped to slide freely in the channels. If desired the enlarged inner portions of the pivots may be set in blocks 30 of phenolic resin or other plastic shaped to slide between the undercut flanges 29, as shown in Fig. 5.

The pivot pins 25 extend through holes 31 in stamped metal plates 32 fastened to the ends of the sash at its upper corners. These plates not only serve as a part of each hinge unit but also as means for connecting the sashes to the travel bars or links 27. In effect the plates are bell cranks fulcrumed on the pins 25 and having two arms 33 and 34. The arm 33 is long and has openings 35 to receive screws 36 which fasten it to the web portion of an end section of a sash. The arm 34 is short and extends in a direction substantially at right angles to the length of the arm 33. The arm 34 extends in overlapping relation to the adjacent travel link 27 and has an opening 37 to receive a pivot stud 38 carried by that link. The arm 34 is laterally offset from the portion of the plate having the pivot opening 31, and the straight portion of the arm 33 is still further offset in the same direction to properly dispose these parts in the hollow jamb. Power transfer links 40, later de-

scribed, are mounted on the pivot studs 38 associated with the lower sash and are disposed between the transfer links and the arms 34, as shown in Fig. 4. Spacing washers 41 are on the studs 38 associated with the upper sash between the transfer links and the arms 34 as shown in Fig. 3. These parts are removably retained on the studs 38 and the plates 32 are removably held on the pivots 25 by spring clips engaged with grooves in the projecting ends of the studs and pivots as shown in some of the figures of the drawings.

The fulcrum links 28, which cause sashes to swing as the slides 30 carrying the pivots 25 move up and down in the guide channels 26, have their upper ends suitably pivoted to the ends of a sash and their lower ends mounted on pivots 43 which are vertically adjustable on the jambs. The upper ends of the links 28 of each pair are preferably mounted on pivots 44 formed by rivets set in laterally offset portions 45 of the arms 33 of the plates 32. These plates thus serve several purposes and not only simplify the structure but reduce the cost of manufacture. The pivots 43 are pins carried by cast bracket members 46 slidably adjustable in the guide channels 26. The brackets 46, as seen in Figs. 8 and 9, comprise flat and elongated plates with their edges slideable in the undercut flanges 29 and arms 47 which are offset from the intermediate portions of the plates and project in a forward direction. The pivots 43 are studs which project laterally from the arms and are retained in pivot openings in the links 28 by spring clips. The plates are freely slideable in the flanges 29 and may be fastened in adjusted positions by screws 48 threaded through their end portions and adapted to thrust against the bottom of the guide channel 26. This construction permits quick and easy adjustment of a sash by merely loosening the screws, relocating the pivot carrying member or bracket and then tightening the screws.

It will be seen that the above described structure will enable the sashes to be more effectively moved and held in their fully closed positions without applying undue force from the operator to the travel links 27, since the latter are laterally off-set in the jambs from the guides 26, 29 which cause the sash fulcrums 25 to move vertically, the arms 47 to which the lower ends of the fulcrum links 28 are pivoted project laterally from the guides in the direction of the travel link, and the short arms 34 of the bell-crank plates also project laterally from the guides and the sashes. Thus when the travel links are moved upwardly force is applied to the laterally projecting arms 34 which are rigid with the sashes and disposed adjacent the pivots 25 thereof, and the bottoms of the sashes will be more effectively forced to closed positions. That operation is facilitated by having the pivots 43 for the lower ends of the fulcrum links 28 off-set from the plane of travel of the sash fulcrums 25.

While any suitable mechanism may be provided for simultaneously sliding the travel links 27, I have shown the lower ends of the links 40 pivoted to power arms 50 projecting radially from a torque shaft 51 mounted in the sill. The arm 50 at the right hand side of the frame has pivoted to its intermediate portion a pair of links 52, the opposite ends of which are mounted on pivot studs on a nut 53 adapted to travel on a vertical screw 54. The latter is on a shaft 55 journaled in bearings on a casting 56 disposed in an opening in the inner or front wall of the jamb 20. This casting is fastened by screws 57 to a cast casing 58 fastened by screws 59 to the front of the jamb as seen in Fig. 11. Fixed to the lower end of the screw shaft is a beveled gear 60 in mesh with a similar gear 61 fixed to a forwardly extending shaft 62 journaled in the casting 56 and projecting through the casing 58. A hand crank 68 is removably fastened to the shaft 62 for operating the screw shaft and causing the nut 53 to travel on the screw. On the casting 56 is a bearing for one end of the torque shaft 51, the other end of which is mounted in a bearing in the sill be-

neath the other jamb 21. A snap-in resilient sheet metal cover 66, as shown in Fig. 2, closes the open portion of the sill above the torque shaft. A drip cap 64 may be provided at the front of the jamb. Rubber weatherstrips 67 may be provided around the opening in the frame for engagement by the sashes, and a similar strip may extend across the top of the lower sash. These strips are set in grooves in the extruded sections composing the frame and sashes.

From the foregoing, taken in connection with the accompanying drawing, it will be seen that novel and advantageous provision has been made for carrying out the objects of the invention, and while preferences have been disclosed, attention is invited to the possibility of making variations within the scope of the invention as claimed.

I claim:

1. An awning type window assembly comprising a rectangular metal frame having hollow jambs formed by extruded metal sections, a tier of sashes swingably supported within the frame, opposed upright guides within the jambs, each of said guides being formed by a pair of opposed L-shaped flanges integral with the inner face of the outer walls of a hollow jamb, said opposed flanges forming an undercut channel and extending from a point adjacent the top of the jamb to a point spaced above its bottom, a pair of slide blocks for each sash slideable in said undercut guide channels, pivot pins carried by the blocks and about which the respective sashes swing, additional pivot pins in said jambs carried by and movable with said sashes and laterally offset from the first mentioned pivot pins, a travel link in each jamb connecting the said additional pivot pins therein, a pair of fulcrum links for each sash, pivots connecting the upper ends of each pair of fulcrum links to the end portions of a sash, pivots for the lower ends of each pair of fulcrum links, a pair of bracket plates for each sash slideably adjustable in the said undercut guide channels, said bracket plates carrying the last mentioned pivots for the lower ends of the respective pairs of fulcrum links, screws threaded in said bracket plates and thrusting against the bottoms of the said channels to fasten said bracket plates in adjusted positions, and means for simultaneously sliding said travel links.

2. The structure of claim 1 in which the mounting of the sashes includes a pair of bell crank plates for each sash, said bell crank plates having pivot openings to receive the said first mentioned pivot pins carried by the slide block and also having long and short arms, the short arms being disposed in overlapping relation to the respective travel links and having openings to receive said additional pivot pins, said long arms being fixed to the end portions of the respective sashes and having laterally offset portions to which said pivots for the upper ends of the respective pairs of fulcrum links are connected.

3. An awning type window assembly comprising a rectangular metal frame having hollow jambs formed by extruded metal sections, a tier of swingable sashes within the frame, opposed upright guides within the jambs, each of said guides being formed by a pair of opposed L-shaped flanges integral with the inner face of the outer walls of a hollow jamb, said opposed flanges forming an undercut channel and extending from a point adjacent the top of the jamb to a point adjacent its bottom, a pair of opposed slide blocks for each sash slideable in certain portions of said undercut guide channels, sash pivot pins carried by the blocks, a travel link in each of said jambs disposed laterally of said guides, a pair of bell crank plates for each sash, said bell crank plates having pivot openings receiving the said pivot pins and also having long and short arms, the long arms being fixed to the upper portions of the ends of the respective sashes, the short arms projecting laterally from the sashes and being disposed in overlapping relation to the respective travel

links and pivotally connected thereto, a pair of fulcrum links for each sash having their upper ends pivoted to the end portions of the respective sashes, pivots for the lower ends of said fulcrum links, a pair of opposed bracket plates for each sash slidable in other portions of the said guides and having laterally projecting arms carrying the respective pivots for the lower ends of the fulcrum links, means fastening said bracket plates in adjusted positions in said guides, and means for simultaneously sliding said travel links.

4. An awning-type window assembly comprising a rectangular metal frame including hollow jambs, a tier of sashes swingably supported within the frame, opposed upright guides within the jambs, a pair of slides for each sash mounted in said guides and carrying opposed pivot pins about which the respective sashes swing, a pair of bell cranks on each sash adjacent its pivotal mounting, each of said bell-cranks being a plate having short and long arms with an intermediate pivot opening to receive the pivot pin on one of said slides, a travel link in each 15 jamb to which the respective short arms are pivotally

connected, a pair of fulcrum links for each sash with pivots connecting their upper ends to the end portions of that sash, pivots for the lower ends of the fulcrum links of each pair, means in said jambs mounting the last mentioned pivots for independent vertical adjustment, and means for simultaneously sliding said travel links, said long arms of the bell-cranks being fixed to the end portions of the respective sashes and having laterally offset portions to which said pivots for the upper ends of the respective pairs of fulcrum links are connected.
